UNITED STATES PATENT OFFICE.

HENRY E. HADDOCK, OF PHILADELPHIA, PENNSYLVANIA, ASSIGNOR TO
JOHN A. BRILL, OF PHILADELPHIA, PENNSYLVANIA.

SAND-BOX FOR RAILWAY-CARS OR THE LIKE.

SPECIFICATION forming part of Letters Patent No. 739,803, dated September 22, 1903.
Application filed January 14, 1903. Serial No. 138,957. (No model.)

To all whom it may concern:

Be it known that I, HENRY E. HADDOCK, a citizen of the United States, and a resident of the city of Philadelphia, county of Philadelphia, and State of Pennsylvania, have invented 5 certain new and useful Improvements in Sand-Boxes for Railway-Cars or the Like, of which the following is a specification.

The object of my invention is to provide a 10 sand-box which will supply sand promptly and efficiently whenever desired to the track-rails, and this I accomplish by means of a mechanism which has an oscillating gate or bottom adapted to receive and feed the sand 15 from a hopper instead of the usual sliding or otherwise movable valve.

The present invention also resides in certain details of construction, for a more particular description of which reference is had 20 to the accompanying drawings, forming a part of this specification, in which one embodiment of the invention is disclosed.

Figure 1 is a side elevation of my improved sand-box and a part of the car-floor to which 25 it may be attached. Fig. 2 is a plan view of the same. Fig. 3 is a section taken on the line 3 3 of Fig. 4 looking in the direction of the arrows. Fig. 4 is a section on the line 4 4 of Fig. 3 looking in the direction of the 30 arrows. Fig. 5 is a perspective view of the gate or body.

Throughout the various views similar reference characters designate similar parts.

To a car-flooring (or other suitable support) 35 1 is secured a hopper 2, which is preferably made in the form of an inverted truncated pyramid, and extending inwardly from its lower edge is a flange 3, through which pass bolts 4, which secure the hopper to the floor 40 1, defining an opening 3^a in the bottom of the hopper. Adjacent to the inner edge of the flange 3 is a rectangular opening 5 in the floor 1, in which is secured the vertical wall 6 of an inverted conical chute having an open 45 bottom 7^a, and this wall 6 at its lower extremity is joined by the horizontal flange 8, which fits the floor 1 of the car. The chute 7 is surrounded on all except its upper side by the casing 9, which is reduced in diameter below the chute 7, to which a tubular projection 50 10, to receive any suitable connection, as a

nipple 10^a, may be secured. To this a rubber hose or other form of tube (not shown) may be attached. At the upper edge of the casing 9 and on its outer sides are horizontal 55 flanges 11, through which the bolts 4 pass to secure these flanges to the flanges 3 and 8 and the floor 1 in the manner shown in Fig. 3. In the upper edges of the sides of the casing 9 and about equidistant from the 60 flanges 11 are recesses 12, open at the top and which form bearings or pivots or trunnions 13, extending from the sides or webs 14 of the bottom or gate 15, hereinafter described. The inclosure of the chute 7 within the casing 9 forms a protective air-space for sand contained in the hopper and chute, at the same time providing a working space for the bottom or gate, whereby it receives full protection from exterior deranging influences. 70

The general arrangement of flanges in the hopper, chute, and casing and the recesses 12 in the latter enables the parts to be expeditiously assembled in place and to be removed for the purpose of repair, &c. 75

The trunnions 13 are circular in cross-section at 13^a to form bands which engage the walls of the recesses 12, as shown in Fig. 4, and angular throughout the remainder of their length, so as to enable them to be easily 80 inserted in squared apertures 14^a in the webs 14 of the gate 15, and one free end is prolonged, as at 16, to fit the head of the arm 17, to which it is rigidly secured by means of a gib 18. In addition to the vertical walls 14 85 the gate 13 has a lower curved portion 19, which is preferably disposed on an arc of a circle whose radius is greater than the shortest distance from the pivots 13 to said lower portion, although any desired curvature may be 90 given in lieu thereof—that is to say, the curve of the bottom 19 of the gate 15 is preferably not concentric with and is preferably greater than that of the bearing 13^a. The webs 14 have upwardly and inwardly inclined 95 edges, the lower ends of which terminate in the ends of the bottom.

In the preferred form, as shown, the base 19 of the gate—that is, its operative or sand receiving and dumping element—is disposed 100 in a plane eccentric to that of the pivot. It is better to have the curve as "flat" as pos-

sible, so that sand will not accumulate on said bottom. To prevent any lumps of sand from closing the mechanism, I provide the curved lower portion or base 14 with a stirrer 20, which may be substantially a conical horn, which extends upwardly and inwardly from one side of the center, is inclined to the vertical, and preferably crosses the axis of the trunnions 13. When the gate is swung 10 on its pivots, the horn breaks and stirs up the lumps of sand which would otherwise clog the parts. It will be noted that the stirrer 20 has a greater amplitude of movement at its base than at the plane of the trunnions 15 and, moving through the contracted opening 7^a, thoroughly breaks up and stirs the sand before it reaches the gate.

The casing 9 is provided with lugs 21 22 on each of its outer surfaces adjacent to and at 20 each side of the recesses 12, so that the box may be located at either end of the car and operated from either or both ends, the lugs 22 being below the lugs 21, and through the lugs 22 (but one set of each being in use at 25 the same time) passes a set-screw 23, which may be locked in place by means of a nut 24. The lugs 21 and 22 are placed on both sides of the casing, so that the bottom may be moved from either side as desired. The set-screw 23 and the lug 21 form stops to limit the throw of the link 16 and each engage projections 25 and 26, formed respectively on said link for this purpose, the projection 25 and set-screw 23 forming an adjustable stop, 30 which enables the distance between the base 14 of the gate 15 and the opening 7^a in the chute 7 to be adjusted within certain limits and the opening to be regulated, as shown in dotted lines in Fig. 3, the size of opening 35 varying with the amount of sand to be placed on the track.

The lower end of the arm 17 has a link 27 pivoted thereto, and the other end of the link 27 is pivoted to the lower end of the handle 45 28, which passes up through the floor 1 and is fulcrumed at 29 to a suitable base 29^a. A spring 30 is fastened at one end of the said floor and at the other to the link 27 to normally hold the projection 26 to the lug 21, as 50 shown in Fig. 1. When the upper end of the handle 28 is thrown toward the sand-box 2, the link 16 is swung forward until the projection 25 engages the said screw 23, which is so adjusted as to allow a proper opening between 55 the bottom 15 and hopper 7. Sand may then pass through this opening to the track. When enough sand has passed, the handle is released and the spring restores the bottom to its normal position, thus closing the opening.

60 Having described one embodiment of my invention, what I claim is—

1. A sand-box, a casing, a chute having an open bottom, pendent within the casing, and a gate movable across the said open bottom, 65 and pivots for said gate passing through the casing adjacent the upper edge of the latter.

2. In a sand-box, a chute with a gate swing-

ing on an axis which runs parallel to the bottom of said gate, and located above the same, and means for permitting one end of said bottom to swing under the said chute. 70

3. In a sand-box, a chute, a gate, webs suspending the bottom of said gate, and pivots suspending said webs, the length of said bottom being just sufficient to cover the opening 75 in the chute.

4. In a sand-box, a chute, a gate, webs suspending the bottom of said gate, pivots supporting said webs, and a link fixed to one of said pivots, and a screw for limiting the angular movement of said link. 80

5. In a sand-box, a chute, a pivoted gate suspended under said chute, and adjustable means for limiting the angular movement of said gate. 85

6. In a sand-box, a chute, pivots, and a gate suspended from said pivots, an arm on one of said pivots, and means on said arm for limiting the movement of said gate. 90

7. In a sand-box, a chute having a large 95 opening in its bottom, pivots, and a gate suspended from said pivots, said gate having a bottom curved on the arc of a circle, the radius of which is greater than the shortest distance from said pivots to said bottom. 95

8. As an article of manufacture, a gate for sand-box chutes comprising a bottom, webs with upwardly and inwardly inclined edges extending from said bottom, and pivots in 100 said webs.

9. As an article of manufacture, a gate for sand-box chutes comprising a curved bottom, webs with upwardly and inwardly inclined edges extending from said bottom, and pivots in 105 said webs.

10. As an article of manufacture, a gate for sand-box hoppers, comprising a bottom with a horn extending upwardly therefrom, webs extending from said bottom, and pivots in 110 said webs.

11. In a sand-box, a chute, a gate swinging beneath said chute, and a horn extending upwardly from the bottom of said gate and adjacent to the walls of the chute. 110

12. In a sand-box, a chute, a casing inclosing 115 said chute and secured thereto, and a flange on said chute which separates the casing from the car-flooring.

13. In a sand-box, a chute, a casing inclosing 120 said chute, a flange on said chute which separates the casing from the car-flooring, and a swinging gate for said hopper pivoted to the casing.

14. In a sand-box, a chute, a casing inclosing 125 said chute, and a swinging gate for said chute pivoted adjacent to the top of said casing.

15. In a sand-box, a chute, a casing inclosing 130 said chute, a swinging gate for the said chute pivoted in the casing at the top thereof, and means on said casing to limit the movement of said gate.

16. In a sand-box, a chute, a gate pivoted 135 to swing under the same, a spring for hold-

- ing said gate normally under said chute, and means for moving said gate against the action of the said spring.
17. In a sand-box, a casing with open recesses in the top edge thereof, a gate with trunnions having bearings within said recesses whereby the gate may be lifted out of said casing.
18. In a sand-box, a chute, a gate moving under said chute, and a horn extending upwardly into said chute.
19. In a sand-box, a chute with an opening in its lower portion, a gate swinging under said opening, and a horn extending upwardly from the bottom of said gate, and moving between the walls of said chute.
20. In a sand-box, a chute, a gate pivoted to move under said chute, a horn extending in said chute.
21. In a sand-box, a chute, a gate swinging on pivots under said chute, the bottom of which is curved eccentrically of its pivots.
22. In a sand-box, a chute, a gate swinging under said chute on trunnions located near the top of the chute, the bottom of said gate being curved eccentrically of said trunnions.
23. In a sand-box, the combination in a chute, of a gate having a curved bottom, pivoted above said bottom to swing below the chute, and a stirrer extending upwardly from said gate into the chute, and adapted to swing with said gate.
24. In a sand-box, the combination with a chute, and a swinging gate, of a stirrer extending upwardly from said gate into the chute, and adapted to swing with said gate, the stirrer having a greater amplitude of movement at its base, than at its top.
25. In a sand-box, the combination with a chute, and a swinging gate, of a stirrer extending upwardly from said gate into the chute, and adapted to swing with said gate, the stirrer having its greatest movement at the bottom of the chute.
26. In a sand-box, having a chute with downwardly-inclined sides, and a gate having a curved bottom located below the ends of said sides, and upwardly-extending webs embracing said sides and pivoted adjacent thereto, and means for swinging said gate.
27. In a sand-box, having a rectangular chute with downwardly-inclined sides, and a gate having a curved bottom located below the ends of said sides, and upwardly-extending webs for swinging said gate.
28. In a sand-box, having a chute, with downwardly-inclined sides, and a gate having a curved bottom located below the ends of said sides, and upwardly-extending webs embracing said sides, and pivoted adjacent thereto, and a horn extending upwardly from the bottom of said gate, and means for swinging said gate.
29. In a sand-box having a chute with downwardly-inclined sides, and a gate having a curved bottom located below the ends of said sides, and upwardly-extending webs embracing said sides and pivoted adjacent thereto, an inclined horn extending upwardly from said bottom into said chute, and means for swinging said gate.
30. In a sand-box, having a rectangular chute with downwardly-inclined sides, and a gate having a curved bottom located below the ends of said sides, and upwardly-extending webs embracing said sides, and pivoted adjacent thereto, and a horn extending upwardly from said bottom, and means for swinging said gate.
31. In a sand-box, having a rectangular chute with downwardly-inclined sides, and a gate having a curved bottom located below the ends of said sides, and upwardly-extending webs embracing said sides, and pivoted adjacent thereto, and an inclined horn fixed to said bottom and extending between the sides of said chute, and means for swinging said gate.
32. In a sand-box, having a chute with downwardly-inclined sides, and a flange extending horizontally from the upper edges of said inclined sides, so that the car-flooring will be above said flange, and a casing with a horizontal flange which is adapted to be secured to the flange of the chute.
33. In a sand-box, a casing having a recess in its upper edges which form bearings, trunnions in said bearings, webs suspended therefrom, a curved bottom uniting said webs, and means on one of said trunnions, whereby the trunnions, webs, and bottom are given an angular movement.
- Signed at the city of Philadelphia, county of Philadelphia, and State of Pennsylvania, this 9th day of January, 1902.

HENRY E. HADDOCK.
